UNITED STATES PATENT OFFICE.

WILLIAM V. ORR, OF CLEVELAND, OHIO.

SUCTION CLEANING DEVICE.

1,210,523.

Specification of Letters Patent. Patented Jan. 2, 1917.

Application filed July 9, 1915. Serial No. 38,843.

To all whom it may concern.

Be it known that I, WILLIAM V. ORR, a citizen of the United States, residing at Cleveland, in the county of Cuyahoga and State of Ohio, have invented a certain new and useful Improvement in Suction Cleaning Devices, of which the following is a full, clear, and exact description, reference being had to the accompanying drawings.

This invention relates to suction cleaners of the type comprising a suction device contained in a movable casing and provided with a collecting nozzle adapted to be moved around the floor or floor covering and collect the dust and litter therefrom.

The objects of the invention are the provision of new and improved arrangements for attaching an extension hose thereto whereby an extension tool can be used upon walls, hangings, furniture, and the like; the provision of new and improved means whereby the attachment of the extension hose shall cut off the main collecting nozzle; the provision of new and improved means for retaining the hose connection in place; while further objects and advantages will appear as the description proceeds.

Generally speaking my invention may be defined as consisting of the combinations and constructions recited in the claims annexed hereto and illustrated, in one embodiment, in the drawings accompanying and forming a part of this application wherein:

Figure 1 is a perspective view of a suction cleaner having an extension hose secured thereto according to my invention; Fig. 2 is a vertical longitudinal central section through a part of the nozzle adjacent to its junction with the fan casing, showing the hose connection in operative position; Fig. 3 is a perspective view of the hose connection removed from the cleaner; Fig. 4 is a top plan view of a portion of the nozzle and fan casing, the cover plate being removed; Fig. 5 is a view similar to Fig. 2 showing a modified form of securing device for the hose attachment; and Fig. 6 is a perspective view of the cover plate which is employed when the hose connection is absent.

Describing the parts by reference characters, 1 represents the fan casing of a portable suction cleaner, 2 the motor casing axially secured thereto, and 3 the collecting nozzle which projects obliquely forwardly from the end of the fan casing opposite the motor,

said nozzle increasing in width as it departs from said fan casing and being formed at its extremity with an elongated inlet mouth, transversely arranged, whose plane is substantially parallel to the axis of the fan chamber 1. Said nozzle is supported by means of suitable rollers 6-6 for movement about the floor in the usual manner by means of the handle 7, and the dust and dirt collected is received in a suitable bag 8 secured to an outlet neck 9 projecting from the periphery of the fan chamber.

The interior of the nozzle 3 is formed with one or more passageways establishing communication between the inlet mouth and the opening 12 in the end wall of the fan chamber. The upper and lower walls of said nozzle consist of generally flat triangular plates, 13 and 14 respectively, the former being provided adjacent to the wall of the fan chamber with an aperture 15, normally closed by means of a flat cover plate 16. The part of said aperture nearest to the inlet mouth is curved or semi-circular as shown in Fig. 4, while the other part of the aperture merges with an elongated slit 17 formed immediately adjacent to and parallel with the flat end-wall of the fan chamber 1, and also in alinement with vertical ways 18 formed inside of the nozzle at each side of the aperture 12.

The hose connection consists of a flat metal plate 20 adapted to be inserted edge-wise into the slot 17 and along the ways 18 so as to cover the aperture 12, there being a hose nipple 21 projecting obliquely from the forward face of the plate and adapted to be received by the aperture 15 when the plate is fully seated. A flexible extension hose is secured to this nipple in any suitable or convenient manner. The aperture 15 is preferably of such a size as to allow the nipple to extend freely therethrough, thus facilitating manipulation.

In the construction illustrated in Figs. 1 to 4 inclusive I have shown the upper and lower walls of the nozzle as connected by a wall 24 forming an oval symmetrical deflector extending along the longitudinal axis of the nozzle from a point adjacent the inlet mouth to a point adjacent the opening 12. In the present embodiment this wall 24 defines a recess or cavity which is open upon the bottom of the nozzle but whose top is covered by a web 23. The wall 24 co-operates with the sides of the nozzle to

form two separated passage-ways leading from the suction slot to the opening 12. Projecting through the web 23 upon the center line of the machine, I have shown a longitudinally slidable bolt 25 normally held 5 yieldingly in forward position by means of the spiral spring 26. I have shown this bolt as provided intermediate its ends with a rigid thumb-pin 29 which projects through the slot 30 in the top wall of said recess and also serves as an abutment for the spring 26. The forward end of the bolt 25 is formed for engagement with the boss 31 formed at the lower side of the 10 hose nipple, so that upon the insertion of the plate this bolt will first be pressed back and afterward automatically lock the connection in place. Disengagement of the same is readily effected by moving the pin 29.

15 20 In Fig. 5 I have illustrated a slightly modified construction of hose attachment, wherein the top and bottom walls 13^a and 14^a of the nozzle are unobstructed. In this embodiment I have shown the nipple 21^a as provided with a rigid radial boss 32, apertured for the reception of a rotatable screw 33 adapted to enter a threaded aperture 34 formed in the wall 13^a adjacent to the opening 15^a.

25 30 The cover plate 16, employed when the hose connection is removed and the machine is being used in the usual manner, is preferably of substantially semi-circular shape as shown in Fig. 6, and is secured in place in any suitable manner, preferably by means of a spring clip 35 secured to its underside. A rib 36 is preferably provided for insertion in the slot 17 to fix the position of this 35 plate.

35 40 While I have described the present embodiments in detail, I do not confine myself to such embodiments or limit myself to such details except as the same may be positively recited in the claims hereto annexed or may be rendered necessary by the prior state of the art.

Having thus described my invention, what I claim is:

50 1. In a suction cleaner, a casing having a fan chamber formed with an inlet opening in one of its sides, and a collecting nozzle carried by said casing and surrounding said opening, said nozzle having an aperture in one of its walls at a point adjacent to said casing, adapted to receive a hose connection, and means carried by said casing for securing said connection in place.

55 2. In a suction cleaner, a casing having a substantially cylindrical fan chamber formed with an inlet opening in one of its end walls and a fan shaped collecting nozzle projecting from said end wall and terminating in an inlet mouth whose plane is substantially parallel to the axis of said

fan chamber, said nozzle surrounding said opening and having an aperture in its upper wall at a point adjacent to the end of said fan chamber, and adapted to receive a hose connection into said aperture and to surround said inlet opening.

3. In a suction cleaner, a casing having a fan chamber formed with an inlet opening in one of its sides and a collecting nozzle projecting from said chamber and surrounding said opening, said nozzle having an aperture in one of its side walls at a point adjacent to said casing, a plate adapted to be inserted into said aperture and to be secured against the side of said fan chamber, 75 said plate carrying a hose receiving nipple adapted to register with said inlet opening.

4. In a suction cleaner, a casing having a fan chamber formed with an inlet opening in one of its sides and a collecting nozzle 85 projecting from said chamber and surrounding said opening, said nozzle having a guideway inside each of its side walls at a point adjacent and parallel to the side of said fan chamber, a plate adapted to be slid along said guideways and to cover said opening, said plate carrying a hose receiving nipple adapted to register with said inlet opening, and means carried by said casing inside said nozzle for securing said 90 plate in place.

5. In a suction cleaner, a casing having a fan chamber formed with an inlet opening in one of its walls and a collecting nozzle projecting from said wall and surrounding 100 said opening, said nozzle having an elongated slot therein adjacent to the side of said casing and an aperture merging with said slot, a plate adapted to be slid edge-wise into said nozzle through said slot, said 105 plate carrying a hose connection adapted to register with said inlet opening, said connection when fully seated projecting through said aperture, and means for securing said plate to said casing.

6. In a suction cleaner, a casing having a pump chamber and a collecting nozzle projecting from one wall of said chamber, said wall having an opening therein normally connecting said pump chamber with the interior 115 of said nozzle, and one wall of said nozzle having an aperture therein adjacent to said chamber wall, said aperture being adapted to receive either a cover for closing it or a flat plate projecting edgewise through it and covering said inlet opening, said aperture also being formed to receive and accommodate a hose connection projecting from said plate, and means within said nozzle for securing said plate in place.

7. In a suction cleaner, a casing having a pump chamber one of whose walls is formed with an inlet opening and a fan shaped collecting nozzle projecting therefrom and surrounding said opening, said 120 125 130

5 nozzle having spaced upper and lower walls defining a suction passage and one of said nozzle walls being formed with an aperture adjacent to the wall of said pump chamber, a wall connecting the walls of said nozzle and defining an open recess, a flat plate adapted to be inserted into said aperture and a nipple carried by said plate and adapted to register with said inlet 10 opening, and a slideable bolt located in said recess and adapted to engage said hose connection when in place in said aperture and retain it against displacement.

8. In a suction cleaner, a casing having 15 a pump chamber one of whose walls is formed with an inlet opening and a fan-shaped collecting nozzle projecting therefrom and surrounding said opening, said nozzle having spaced upper and lower walls 20 defining a suction passage and one of said walls being formed with an aperture adjacent to the wall of said pump chamber, a flat plate adapted to be inserted into said aperture and a nipple carried by said plate 25 and adapted to register with said inlet opening, a slideable spring bolt located in the longitudinal axis of said nozzle and adapted to engage said hose connection when in place in said aperture and retain 30 it against displacement, and means for retracting said bolt.

9. In a suction cleaner, a casing having a pump chamber one of whose walls is formed with an inlet opening, and a col-

lecting nozzle projecting from said wall 35 and surrounding said opening, one of the walls of said nozzle being formed adjacent to the wall of said pump chamber with an aperture adapted to receive either a cover 40 for closing it or a flat plate covering said inlet opening, said last plate having an inclined hose nipple adapted to project out through said aperture when said plate is in place against said inlet opening.

10. In a suction cleaner, a casing having a pump chamber one of whose walls is formed with an inlet opening, and a collecting nozzle projecting from said wall and surrounding said opening, the direction of said nozzle being oblique to the axis 50 of said chamber, one of the walls of said nozzle being formed adjacent to the wall of said pump chamber with an aperture, and a flat plate adapted to enter said aperture and to cover said inlet opening, and an inclined hose nipple integral with said plate adapted to project out through said aperture when said plate is in place against said inlet opening, said nipple being obliquely inclined with respect to said plate.

In testimony whereof, I hereunto affix my signature in the presence of two witnesses.
